[57] CLAIM

The ornamental design for a combined ink roller and holder therefor, as shown and described.

DESCRIPTION

FIG. 1 is a top plan view of a combined ink roller and holder therefor showing my new design;

FIG. 2 is one side elevational view thereof, it being understood that the opposite side elevational view thereof would be a mirror image;

FIG. 3 is a bottom plan view thereof;

FIG. 4 is a front elevational view thereof;

FIG. 5 is a rear elevational view thereof;

FIG. 6 is a perspective view thereof;

FIG. 7 is a top plan view of a combined ink roller and holder therefor showing a modified form of my new design;

FIG. 8 is one side elevational view of the modified form thereof, it being understood that the opposite side elevational view would be a mirror image;

FIG. 9 is a bottom plan view of the modified form thereof;

FIG. 10 is a front elevational view of the modified form thereof;

FIG. 11 is a rear elevational view of the modified form thereof;

FIG. 12 is a perspective view of the modified form thereof.

FIG. 13 is a cross-sectional view of the second embodiment of the ink roller holder along the line 13—13 in FIG. 8;

FIG. 14 is a perspective view of the second embodiment of ink roller holder.
